[57] CLAIM

The ornamental design for a document feeder for a
copying machine, as shown and described.

DESCRIPTION

FIG. 1 is a front, top and right side perspective view of
a document feeder for a copying machine showing our
new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, the broken line
showing of a copying machine is environmental only
and forms no part of the claimed design.
